UNITED STATES PATENT OFFICE.

GEORGE A. E. JONES, OF NEW LONDON, CONNECTICUT, ASSIGNOR TO UNITED STATES ELECTRIC COMPANY, A CORPORATION OF CONNECTICUT.

APPARATUS FOR HEATING RIVETS.

1,313,539.

Specification of Letters Patent. Patented Aug. 19, 1919.

Application filed April 25, 1919. Serial No. 292,543.

To all whom it may concern:

Be it known that I, GEORGE A. E. JONES, a citizen of the United States, and a resident of New London and county of New London 5 and State of Connecticut, have invented an Improvement in Apparatus for Heating Rivets, of which the following description, in connection with the accompanying drawings, is a specification, like reference characters on the drawings representing like parts.

This invention relates to an apparatus for heating rivets by passing an electric current therethrough after the cold rivets 10 have been inserted in the holes in the structural parts to be united by them.

In Patent No. 1,297,570 granted to me March 18, 1919, I have shown electrodes to be applied to the point and head of the 15 rivet, respectively, so that the current passes from one electrode to the other through the rivet. In such construction, it is necessary to have electric connections from the electrodes to the transformer or source of electric current at both sides of the structure 20 in which the rivet is contained and it is sometimes difficult to provide adequately for such connections.

In accordance with the present invention, I employ two electrodes connected with the poles of the source of the electric current, and coöperating therewith at the other side of the structure, I employ a bridging connector of large conductivity adapted 25 to make contact with the heads of two rivets simultaneously so that when the electrodes at the other side of the structure are placed in contact with the tips of the said rivets, the current passes from one electrode 30 through the corresponding rivet, to the connecting piece at the other end of said rivet and thence to the other rivet, and through the same to the other electrode, the two rivets being thus interposed in series in the 35 electric circuit and being heated simultaneously.

The invention further consists in the combination of a movable electrode with a rivet heading machine so that the same operator may first apply the electrode to the rivet to be heated and immediately upon withdrawal thereof after the rivet has been 40 properly heated may apply the heading machine to effect the heading of the rivet.

The invention further consists in providing the electrode with internal passages for the circulation of cooling fluid, herein shown as adapted to be placed in communication with the exhaust passage of a pneumatic heading machine so that at the time 45 when the hammer of said machine is operating to head the rivet, the exhaust from the machine will be caused to flow through the body of the electrode and cool the same so that it will not become overheated as is 50 liable to happen if employed for heating rivets in close succession without intervening cooling.

Figure 1, is a diagrammatic view illustrating a rivet heating apparatus employing this invention, showing the rivet connecting or bridging conductor in section, and

Fig. 2, is a sectional detail on a larger scale of one of the electrodes adapted to 55 be used in combination with a pneumatic rivet heading machine.

Referring to Fig. 1, the electrodes 2, 20, which so far as one portion of the invention is concerned may be of any suitable construction such as is exemplified in Patent No. 1,297,570 above referred to, are connected by cables 3, 30, of large conductivity with the opposite poles or terminals of the secondary component of a transformer 4, the 60 primary component of which is supplied with electric current from any convenient source. Said electrodes are shown in this instance as mechanically connected, as will be hereinafter described, with rivet heading 65 machines herein shown as pneumatic riveting hammers 5 of usual construction and are employed in conjunction with a bridging connector 6 consisting of a main body portion of copper or material of high conductivity and of large sectional area, adapted 70 to make contact with the heads of two rivets 50, 51 when inserted in the plates 52, 53, or structural parts to be united by the rivets, with their points projecting beyond said 75 plates at the other side of the structure from that at which the connecting bridge 6 is located.

For convenience and safety in manipulation, the connector 6 is inclosed in insulating 80 material 7 covered by a protecting shield 8 which may be of iron or of other durable material, and a handle 9 is provided to fa-

cilitate the manipulation of the bridge by an attendant or operator at the side of the structural parts at which the heads of the rivets are to be heated.

- 5 To insure the proper coöperative relation between the electrode 2 or 20, and the corresponding heading machine 5, the latter is provided with a bracket or supporting piece 12 fixed thereto near the end of the 10 heading machine at which the hammer thereof is to engage the rivet, said bracket having a guiding passage 13, (see Fig. 2), in which the correspondng electrode is longitudinally movable.
- 15 A spring 14 tends to pull the electrode rearwardly relative to the heading machine and when free to act holds the said electrode with a stop shoulder 14, (see Fig. 2), against the guide 13, in which position 20 the contacting tip of the electrode is some distance rearward from the rivet engaging end of the heading machine and consequently does not interfere with the free manipulation of said machine in heading the 25 rivet after it has been heated by the passage of the current therethrough.

In the use of the apparatus the rivets are cold when inserted in the rivet holes, and the operator on the side at which the heads 30 are located presses the bridge 6 against the heads of two rivets, thus providing a much less resistant electric connection between them than what is afforded by the plates or structural parts 52, 53 in the holes of 35 which the rivets are inserted.

The operators at the other side of the structural parts 52, 53 then press the electrodes 2, 20, against the projecting ends of the two rivets, the heads of which are 40 bridged by the connector 6, the said electrodes being moved into and held in forward position relative to the heading machine as is permitted by the expansion of the springs 14 so that the heading machines 45 will not interfere with the proper application of the electrodes to the ends of the rivets.

The current from the transformer then flows through the two rivets in series and 50 quickly heats the same to the proper temperature and softness for the heading operation whereupon the electrodes 2, 20 are released and are drawn back out of the way by the springs 14 and the heading machines 55 5 are applied to the tips of the rivets and set in operation to head the rivets in the usual wav. a suitable abutment or holder-on being applied to the rivet head.

Referring to Fig. 2 which shows the construction of one of the electrodes such as 2 or 20 employed in connection with a pneumatic rivet heading machine, it will be seen that the main body portion is inclosed in an insulating cover 21, which is in turn inclosed 65 in a protecting shield 22 which may be of

iron, the electrode being in this respect substantially like that shown in my former patent, hereinbefore referred to.

In accordance with the present invention however the main body portion 2 of the 70 electrode is provided with internal passages 25, 26, distributed through it, the passages 26 being shown as communicating with a space 27 surrounding the body 2 within the insulating covering 21, the said space or 75 jacket communicating by passages 28 near the projecting contacting end of the electrode with the surrounding atmosphere.

The passage 25 is adapted to receive a cooling fluid, to be passed through the passages 25, 26, and jacket space 27 from which it may be discharged through the passages 28. In the present example of the invention, said fluid inlet passage 25 is connected by a flexible pipe 24 with the exhaust passage of 85 the pneumatic rivet heading machine, the result being that when said machine is in operation heading the rivet, the exhaust therefrom will be caused to flow through the passages 25, 26 and the jacket space 27, and to 90 escape by the passages 28 to the atmosphere, thus cooling the main body of the electrode, so that it does not become overheated as is liable to occur if employed to heat several rivets in succession with only such intervals 95 between the heating operations as may be occupied in performing the heading operation, which in practice requires only a small fraction of a minute for its performance.

The hose for supplying the compressed air 100 by which the heading machine is operated is indicated at 29.

The bridging connector 6 is shown as provided with a slightly projecting ledge 60 across one end and along one side of the 105 contacting face, which affords a slight shoulder projecting from the contacting face, which may engage with the head of the rivet when in an approximately vertical plane, thus sustaining the weight of the connector and making it easier for the operator to keep it pressed in contact with the rivet heads without liability of slipping off.

For an embodiment of that part of the invention which provides for the heating 115 of two rivets simultaneously, it is not essential that the electrodes 2, 20 should be constructed as described, or that one or both of them should be combined or mechanically associated with a heading machine as shown, and in some cases it may be desirable to use but one heading machine in connection with two electrodes, the heading machine being employed to head the rivets consecutively after they have been heated simultaneously, 120 the second rivet retaining sufficient heat during the short time required for heading the first rivet.

What I claim is:

1. An apparatus for heating rivets after 130

insertion in structural parts to be riveted thereby, comprising two contacting electrodes adapted to be placed in contact with the tips of the rivets to be heated, and being connected with the two poles respectively of a suitable source of electric current, and a bridging connecting piece of large conductivity adapted to be placed in contact with the heads of the two rivets with the tips of which the electrodes are to make contact, substantially as described.

2. The combination with a portable rivet heading machine, of an electrode, and supporting and guiding means therefor connected with said heading machine, said electrode being movable relative to the heading machine, whereby the contacting end of the electrode may be advanced beyond the end of the heading machine or withdrawn to the rear thereof.

3. The combination of a rivet heading machine, with a contact electrode and guiding support therefor connected with said heading machine, said electrode being movable to advance its contacting end beyond the end of the heading machine, and a

spring to retract said electrode, and stop to limit the movement under the action of said spring, substantially as described.

4. An electrode for heating rivets comprising a main body portion of conducting material and a protecting shield surrounding the same with an inclosed space between said electrode body and shield, said electrode body being provided with a longitudinal internal passage and with a number of passages connecting the same with the space within the shield, and there being passages from said space to the external air, substantially as and for the purpose described.

5. The combination with a pneumatic heading machine, of an electrode, and supporting and guiding means therefor connected with said heading machine, said electrode being provided with internal circulating passages communicating with the exhaust passage of the heading machine, substantially as and for the purpose described.

In testimony whereof, I have signed my name to this specification.

GEORGE A. E. JONES.
